APPARATUS FOR ABRADING BISQUE WARE

Oscar J. Burden, Alliance, Ohio

Application December 17, 1951, Serial No. 262,065

5 Claims. (Cl. 51—7)

1

The invention relates generally to the abrading or cleaning of chinaware after it has been fired in a bisque kiln and before it is glazed, and more particularly to a novel method and apparatus by which the ware is abraded or cleaned continuously without substantial breakage.

It is necessary to abrade ware at the bisque stage to remove particles of sand and clay and foreign matter which would project through or cause roughness in the glaze subsequently to be applied, or which would interfere with decorating underglaze ware. Prior abrading practice has included hand sanding, which is obviously slow and expensive, and sand blasting, which produces spotty and uneven cleaning. Another prior practice is to tumble the ware with gravel or granular material in a closed frame. All of these prior methods are of the batch type in which one or more of the articles of ware are put in position by hand for cleaning, and later removed by hand.

A more recent prior method which attempts to clean the ware continuously comprises feeding ware together with grog consisting of gravel and broken pieces of chinaware into the upper end of an axially rotating slightly inclined tunnel-shaped belt, in which the ware is tumbled with the grog and is discharged continuously from the lower end of the belt. This method has several serious disadvantages. For example, the tumbling action results in considerable breakage of the ware; the tunnel-shaped belt is quite long and therefore expensive and the apparatus requires a large amount of floor space; several workmen are required at the discharge end to dump the grog out of the individual pieces of ware; and the ware has too much dust on its surface even after the individual pieces have been dumped.

It is an object of the present invention to provide a novel method and apparatus for continuously abrading bisque ware, so as to overcome the foregoing disadvantages.

More specifically, it is an object of the present invention to provide novel apparatus for continuously abrading bisque ware without substantial breakage and with a minimum amount of labor and expense.

Another object is to provide a novel apparatus which is relatively simple to construct and operate and occupies a small amount of floor space.

A further object is to provide a novel method of continuously abrading bisque ware economically and without substantial breakage.

These and other objects are accomplished by

2

the parts, methods, combinations and constructions comprising the present invention, a preferred embodiment of the novel apparatus being illustrated by way of example in the accompanying drawings, the novel method and apparatus being described in detail in the accompanying specification, the scope of the invention being defined in the appended claims, and the nature of the invention being set forth in the following general statement.

In general terms, the invention includes distributing gravel or grog from an upper perforate tray or hopper into a perforate vibrating or shaking tray having an open discharge end, placing the ware on the vibrating tray for being continuously abraded and advanced thereover to be discharged onto a perforated conveyer belt allowing grog carried over a drop through the belt, the ware on the belt being brushed clean by a brush mounted over the belt, the grog dropping through the vibrating tray being collected on a second conveyor belt, with means for selectively vibrating said second belt when additional ware is placed on the belt, there being means for collecting grog from the shaking tray and from both belts, and means for returning said grog to the upper distributing tray.

Referring to the drawings in which a preferred embodiment of the invention is shown by way of example;

Figure 1 is a plan view of the novel apparatus for carrying out the invention, part of the conveyer for delivering the abraded ware being broken away;

Fig. 2 is a side elevation thereof partly in section;

Fig. 3 is a transverse section as on line 3—3, Fig. 2, showing an end elevation of the principal part of the apparatus;

Fig. 4 is an enlarged transverse section substantially on line 4—4, Fig. 2;

Fig. 5 is an enlarged fragmentary transverse section as on line 5—5, Fig. 2; and

Fig. 6 is a fragmentary transverse section as on line 6—6, Fig. 2.

Similar numerals refer to similar parts throughout the drawings.

The novel apparatus preferably includes a frame having two pairs of upright channel posts 50 tied together at their upper ends by transverse channels 11. Suitable bracing may be provided for the frame members, but the same has not been shown on the drawings for the sake of clarity.

An upper pan or hopper 12 is suspended be-

tween the posts 11 in a preferably slightly inclined position as shown in Fig. 2, and the pan 12 is provided with walls 13 and 14 enclosing the sides and ends of the pan. The pan 12 may be suspended from the transverse channels 11 by links 15 and 16 which are pivoted at their upper ends in brackets 17 secured in the channels, and are pivoted at their lower ends in bracket ears 18 attached to the side walls 13 of the pan 12.

In order to agitate the pan 12, a pitman link 19 is attached to an ear 20 on the lower end of the pan, the pitman being eccentrically connected at its other end to a shaft 21 driven by a motor 22 supported on a platform 23 which is carried by laterally opposite posts 10, the platform being braced by diagonal angles 24.

The bottom wall 25 of the pan 12 is provided with a plurality of perforations 26 which are of a size permitting gradual passage of grog including gravel and the like used for polishing or abrading the bisque ware. A number of transverse slides 27 are slidably mounted under the bottom wall 25, and these slides have perforations 26' adapted to register with the perforations 26. By adjusting the slides transversely, the perforations 26 may be closed so as to control the amount of grog passing through the bottom wall of the pan 12.

A vibrating open-ended tray 29 or chute is suspended between the posts 11 below the pan 12 and preferably inclined so as to be parallel therewith. The side walls 30 of the tray have angle brackets 31 attached to their opposite end portions and the horizontal leg of each angle rests on the top of a helical compression spring 32, the bottom ends of the springs being supported on angle brackets 33 attached to the posts 10. Thus the tray is yieldingly supported by the springs 32 on the posts 10.

The bottom wall 34 of the tray 29 is provided with a plurality of perforations 35 similar to the perforations 26 in the bottom wall of the pan 12, and is also provided with perforated slides 36 similar to the slides 27 for opening and closing a number of the holes 35 in the tray 29. Preferably the tray 29 is vibrated by a wobbler shaft 37 which is journaled in laterally spaced bearings 38 on the bottom wall of the tray, and which has eccentrically weighted discs 39 thereon for imparting a wobbling or vibrating motion to the tray when the shaft 37 is connected by coupling 37' to driving motor 40 supported on the sub-frame indicated generally at 41. Due to the inclination of the tray 29, the grog will slowly advance over the bottom surface of the tray as the same is vibrated, toward the lower end of the tray, or from left to right as viewed in Fig. 2. Consequently, any dishes D which may be supported on the bed of grog carried by the tray will be correspondingly advanced to the right. As shown, the lower discharge end of the tray 29 preferably has mounted thereon a roller 42 journaled in bracket ears 43, over which the dishes D ride as they leave the tray, so that the dishes are more gradually lowered from the tray to avoid unduly jarring the same.

It will be understood that instead of vibrating the tray 29 with a wobbler shaft, a shaker motion may be imparted to the tray by suitable and well known eccentric means, without departing from the scope of the invention.

An endless belt 44 of rubber or rubber and fabric composition is positioned between the laterally opposite posts 10 immediately below the vibrating tray 29. This belt 44 is preferably hori-

zontal and is carried at one end by a roller 45 on a shaft 46 driven by a motor 47 supported on the frame bracket indicated generally at 48. The other end of the belt 44 is carried on an idler roller 49, and the shafts of the rollers 45 and 49 are preferably yieldingly mounted on compression springs 50 carried on brackets 51 attached to the posts 10.

Between the rollers 45 and 49 are a series of supporting idler rollers 52 which have their ends journaled in longitudinal frame members 53, as shown in Fig. 5, the ends of the frame members 53 being journaled on the shafts of the end rollers 45 and 49. Longitudinal guide bars 54 are attached to the upper edges of the frame members 53 by straps 55 for the purpose of holding the outer edges of the upper run 44' of the belt in an upturned position to retain the grog thereon, as best shown in Fig. 5.

In the normal operation of the belt 44, the upper run 44' is operated to travel to the right as viewed in Fig. 2 so that the belt will collect the grog dropping through the perforations 35 in the tray 29, and discharge such material over the end of the belt at the roller 49. However, in case it may be desirable to place large dishes, cups, etc., on the upper run of the belt 44' for the purpose of carrying out an abrading operation on the belt, utilizing the grog deposited thereon, means is provided for vibrating the belt as it travels toward the right. As best shown in Fig. 4, such means preferably includes a wobbler shaft 56 journaled in the frame bars 53 and carrying the eccentrically loaded discs 57. The shaft 56 is coupled by coupling 56' to a driving motor 58 mounted on a platform 59 which may be embodied in the sub-frame indicated generally at 41. Thus when the motor 58 is operating, a vibrating motion will be imparted to the rollers carrying the belt 44 so that any dishes resting upon grog carried on the upper run of the belt will be abraded by the vibrating bed of grog thereon, and the grog dropping from tray 29. When this operation is being carried out on the belt 44, it may be necessary to raise the lower end of tray 29 somewhat so that the dishes on the belt will pass thereunder.

A delivery conveyer belt 60 is mounted on suitable rollers or pulleys with its receiving end extending under the discharge end of the belt 44, said receiving end passing over the idler pulley 61 mounted on brackets 62 attached to laterally opposite posts 10. As indicated in Fig. 1, the belt 60 is perforated and has a large number of relatively large perforations 63 through which the grog carried over from the vibrating tray or the belt 44 or the dishes, can pass. A hopper 64 is mounted on a frame 65 under the receiving portion of the belt 60 to collect all material which is discharged from the tray 29 and the belt 44.

At one end of the hopper is a chute 66 for directing the grog from the hopper onto the lower end of an elevator belt 67 having bucket-shaped flights 68 thereon for carrying the grog upwardly. The lower end of the belt may be carried on a drive pulley 70 which is driven by a motor 71, and the upper end passes over a pulley 72 mounted on brackets 73 which are carried on channel supports 74. A receiving hopper 75 with a connecting discharge chute 76 is mounted under the upper end of the belt 67 for catching the grog elevated by the belt and for returning it to the upper pan 12. It may be desirable to provide a screen under the chute 66 or above the

hopper 75 for screening out any broken pieces of dishes from the grog.

In the operation of the novel apparatus, the grog in the pan 12 is constantly agitated and drops through the perforations 26 onto the vibrating tray 29, the slides 27 and 36 being adjusted so that a bed of grog is carried on the tray 29 and gradually advanced towards its lower end as it is vibrated. An operator stands at the left of the apparatus, as viewed in Fig. 2 and continually places dishes D right side up on the bed of grog. As the dishes gradually progress to the lower right end of the tray, due to the vibrating action and the incline of the tray they are partly covered by grog dropping from pan 12, and all surfaces of the dishes will be abraded or polished by the vibrating material, and will pass over the discharge roller 42 and be received on the upper run of belt 60 without substantial jarring, because the belt is of relatively soft material such as rubber and is positioned close to the roller 42.

As the dishes D are conveyed to the right by the upper run of belt 60, substantially all of the grog will pass through the belt and be collected in the hopper 64, and as the dishes continue to the right, their upper surfaces will be brushed clean of any remaining dust or fine grog material by the rotary brush 78 which is positioned over the upper run of the belt and carried by brackets 79 on the horizontal frame member 65. After the dishes D pass under the brush 78 they are clean and free of dust and are delivered by the belt to a collecting station or to other delivery means.

The operation of the novel apparatus according to the novel method of the invention provides for continuously abrading bisque ware without substantial breakage and with a minimum amount of labor and expense.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiment of the improved construction illustrated and described herein is by way of example, and the scope of the present invention is not limited to the exact details of construction.

Having now described the invention, the construction, the operation and use of a preferred embodiment thereof, and the advantageous new and useful results obtained thereby; the new and useful methods and constructions, and reasonable mechanical equivalents thereof obvious to those skilled in the art, are set forth in the appended claims.

I claim:

1. Apparatus for cleaning bisque ware continuously including a shaker tray having a perforate bottom and an open discharge end, means for distributing grog continuously over said tray bottom, means for vibrating said tray to abrade ware thereon and advance it gradually toward said discharge end, a perforate belt conveyer for receiving material discharged from said shaker tray, brush means for cleaning the dust from ware on said perforate conveyer, a second belt conveyer under said perforate tray for receiving grog dropping through said tray, means for selectively vibrating said second conveyer to abrade ware carried thereon, means for collecting grog from both conveyers, and means for returning said collected grog to said grog distributing means.

2. Apparatus for cleaning bisque ware continuously including a shaker tray having a perforate bottom and an open discharge end, means for distributing grog continuously over said tray bottom, means for vibrating said tray to abrade ware thereon and advance it gradually toward said discharge end, a perforate belt conveyer for receiving material discharged from said shaker tray, a second belt conveyer under said perforate tray for receiving grog dropping through said tray, means for selectively vibrating said second conveyer to abrade ware carried thereon, means for collecting grog from both conveyers, and means for returning said collected grog to said distributing means.

3. Apparatus for cleaning bisque ware continuously including a shaker tray having a perforate bottom and an open discharge end, means for distributing grog continuously over said tray bottom, means for vibrating said tray to abrade ware thereon and advance it gradually toward said discharge end, a perforate belt conveyer for receiving material discharged from said shaker tray, brush means for cleaning the dust from ware on said perforate conveyer, a second belt conveyer under said perforate tray for receiving grog dropping through said tray, means for collecting grog from both conveyers, and means for returning said collected grog to said grog distributing means.

4. Apparatus for cleaning bisque ware continuously including a shaker tray having a perforate bottom and an open discharge end, means for distributing grog continuously over said tray bottom, means for vibrating said tray to abrade ware thereon and advance it gradually toward said discharge end, a perforate belt conveyer for receiving material discharged from said shaker tray, brush means for cleaning the dust from ware on said perforate conveyer, means under said perforate tray for receiving grog dropping through said tray, and means for returning grog from said belt conveyer and from said grog receiving means to said grog distributing means.

5. Apparatus for cleaning bisque ware continuously including a shaker tray having a perforate bottom and an open discharge end, an upper distributing tray for distributing grog over the perforate bottom of said shaker tray, means for vibrating said shaker tray to abrade ware thereon and advance it gradually toward said discharge end, a perforate belt conveyer for receiving material from the discharge end of said shaker tray, a second belt conveyer under said shaker tray for receiving grog dropping through said tray, means for selectively vibrating said second conveyer to abrade ware carried thereon, means for collecting grog from both conveyers, and means for returning said collected grog to said upper distributing tray.
